FASTENER APPLYING DEVICE

John F. Cavanagh, Providence, R. I., assignor to
 Boston Wire Stitcher Company, Portland,
 Maine, a corporation of Maine

Application January 15, 1936, Serial No. 59,256

21 Claims.

(Cl. 1—3)

This invention relates to improvements in fastener-applying devices such as stapling implements for attaching papers and other sheets, for securing tags and labels to articles of commerce and for use generally in fastening or stitching together various other objects.

One object of the present invention is to provide an implement of the type indicated including an arm comprising a magazine for containing a supply of staples and a stapling head mounted on the arm and movable toward and away from the end thereof so that the magazine may be loaded with a supply of staples at the forward end of the implement. 10 Another object of the invention is to provide an implement of the type indicated including means adapted to engage the staples in the magazine to prevent their ejection therefrom and actuated by the head when moved into cooperative relationship with the end of the arm to release the staples. 15

Another object of the invention is to provide an implement of the type indicated having staple-applying mechanism comprising a simple and compact arrangement of elements which may be quickly assembled exteriorly of the implement as a unit and slid into operative position in the head. 25

Another object of the invention is to provide an implement of the type indicated in which the staple-applying mechanism is adjustable longitudinally of the base on which it is mounted for cooperation with either of two spaced pairs of clincher-grooves on the base. 30

Still another object of the invention is to provide an implement of the type indicated with its mechanism so constructed and arranged that in the event of staples becoming jammed therein they may be quickly released by swinging back the head. 35

Further objects of the improvement are set forth in the following specification which describes a preferred form of construction of the invention, by way of example, as illustrated by the accompanying drawings. In the drawings: 40

Fig. 1 is a side elevational view of a staple-applying implement incorporating the improved features constituting the subject-matter of the present invention; 45

Fig. 2 is a top plan view of the implement shown in Fig. 1 illustrated with the actuating knob of the stapling mechanism removed to reveal the cooperative relationship of the elements in the head; 50

Fig. 3 is a front elevational view of the implement shown in Fig. 1; 55

Fig. 4 is a longitudinal sectional view taken on line 4—4 of Fig. 2 showing the stapling arm raised to receive the work therebeneath;

Fig. 5 is a view similar to Fig. 4 showing the relationship of the elements at the completion of 5 a stapling operation;

Fig. 6 is a transverse sectional view taken on line 6—6 of Fig. 5 showing the pivotal mounting for the arm on the base;

Fig. 7 is a transverse sectional view taken on 10 line 7—7 of Fig. 5 showing the staple-driver and the interlocking means for connecting it with the actuating plunger for movement therewith;

Fig. 8 is a longitudinal sectional view of the head taken on line 8—8 of Fig. 2 showing the 15 cooperating pawl-and-ratchet means for preventing return of the staple-driver until a full stroke has been completed;

Fig. 9 is a view similar to Fig. 8 showing the 20 relationship of the pawl-and-ratchet means;

Fig. 10 is a view similar to Fig. 8 showing the relationship of the pawl-and-ratchet means during the return stroke of the staple-driver;

Fig. 11 is a transverse sectional view taken on 25 line 11—11 of Fig. 4 showing the mounting for the staple-retaining pawl on the stapling arm;

Fig. 12 is a view similar to Fig. 1 showing the 30 stapling arm moved longitudinally of the base to align the stapling head with an alternate pair of clincher-grooves;

Fig. 13 is a front elevational view of the implement shown in Fig. 12 with the head and base illustrated as partly broken away and showing the legs of the staples bent outwardly by the 35 clincher-grooves to pin the work;

Fig. 14 is a view similar to Fig. 1 with the head and arm illustrated partly in section and showing the head moved away from the end of the arm to permit the magazine to be loaded with a supply of staples; and 40

Fig. 15 is a front elevational view of the stapling arm and head in the relationship illustrated in Fig. 14.

In general, the present improved implement 45 comprises a base having an arm hinged thereto with a stapling head at its forward end. The arm is constructed as a magazine for holding a supply of staples and the stapling head is pivotally or otherwise suitably mounted on the arm 50 for movement away from the end thereof to provide for loading the magazine with a supply of staples. The head cooperates with the end of the arm to provide a throat through which the staples are driven and means are provided for 55

latching the head in cooperative relationship with the end of the arm. Staple-applying mechanism carried by the head is adapted to be assembled exteriorly of the implement and slid into the head as a unit. The staple-applying mechanism in the head cooperates with an anvil on the base having spaced pairs of oppositely-directed clincher-grooves, and the arm is movable longitudinally of the base for alining the staple-applying mechanism with either one or the other of the pairs of clincher-grooves.

Referring to the drawings, the improved implement as herein illustrated comprises a base 2, preferably made of sheet-metal and of hollow construction embodying a generally flat top 3 bordered by an overhanging beveled flange or rim 4. At its forward end the base 2 has a raised portion 5 with a depression 6 formed therein for receiving a clincher-anvil 7. The upper face of the anvil 7 has a forwardly-positioned pair of clincher-grooves 8 for clinching the legs of a staple 9 inwardly as shown in Figs. 1 and 7; and a second pair of clincher-grooves 9 spaced rearwardly of the grooves 8 for bending the ends of the legs outwardly as shown in Figs. 1 and 13. On the under side of the base 2 below the anvil 7 is a cleat 10 and the parts are held in assembled relationship by a depending stud 11 on the anvil 7 which extends through the base 2, cleat 10 and a spacer element therebetween with a nut 12 screwed onto the threaded end of the stud and engaging the cleat. As shown in detail in Fig. 7, the cleat 10 extends transversely of the base 2 and has bent portions 13 engaging the opposite beveled sides of the rim 4 and terminating in inwardly-directed end flanges 14. A rubber pad 15 formed with beveled sides is fitted within the base 2 and held in place by the engagement of the flanges 14 with slits 16 in the sides of the pad. To mount the pad 15 the slits 16 are alined with the flanges 14 on the cleat 10 and then slid longitudinally thereof, the central portion of the pad being cut away as at 17 to provide a space for the nut 12.

At its opposite or rearward end the base 2 is provided with laterally-spaced upstanding flanges 20 and 21, preferably formed by the opposite sides or legs of a U-shaped member 23 extending upwardly through laterally-spaced slots in the base, see Figs. 1 and 6. The web 24 of the U-shaped member 23 engages the underside of the base 2 and below the web is a cleat 25, similar to the cleat 10, for holding a rubber pad 26. The member 23 and cleat 25 are held in assembled relationship on the base 2 by a screw 27 which extends through the parts with a nut 28 screwed onto its end to engage the cleat, see Fig. 4. The opposite flanges 20 and 21 have alined arcuately shaped slots 30 and 31 and mounted on the base 2 between the flanges is a U-shaped leaf-spring 32 having spaced legs 33 which are bowed to aline with the central portion of the slots at the inner sides of the flanges. The spring 32 embraces the screw 27 and is held in place on the base by the engagement of the head of the screw therewith. A leaf-spring 34 is mounted on the underside of the base intermediate its ends by means of a rivet, bolt 35 or the like passing through the base and one end of the spring. The opposite free end 70 of the spring 34 supports a button or plug 36 which extends upwardly through a suitable aperture 37 in the base. Preferably, the button 36 has a reduced stem 38 projecting from its bottom through a hole in the spring 32.

75 The stapling arm 40 is pivotally mounted be-

tween the flanges 20 and 21 on the base 2, the arm being preferably constructed from sheet-metal folded into channel shape with the upper edges of its sides bent inwardly to provide overhanging lateral flanges 41, see Figs. 4 and 11. The bottom wall 42 of the arm 40 is slotted adjacent its rearward end to form a narrow longitudinally-extending strap 43 which is bent downwardly and deformed to provide a bearing groove 44 at its center as shown in Fig. 4. The arm 40 fits closely between the flanges 20 and 21 and the width of the strap 43 is such as to fit closely between the opposite legs 33 of the U-shaped spring 32, see Fig. 6. A pivot-pin 45 extends through the curved slots 30 and 31 in the flanges 20 and 21 and through the bearing groove 44 in the strap 43 in abutting relation to the under side of the arm 40, being engaged by the opposite legs 33 of the spring 32 to hold it at either one or the other end of the curved slots. By sliding the arm 40 longitudinally of the base 2 the pivot-pin 45 may be transferred from one end to the other of the slots 30 and 31, the legs 33 of the spring 32 yielding to permit movement of the pin. The arm 40 when so mounted is yieldingly held with its forward end in its raised position by the resiliently mounted button 36 engaging its under side.

Extending longitudinally of the channel of the arm 40 is a staple-core 46 constructed of sheet-metal folded into channel shape. The staple-core 46 is secured to the bottom wall 42 of the arm 40 in any suitable manner, such as by the rivets 47 shown in Fig. 4, with its sides spaced inwardly from the sides of the arm and its upper edges terminating short of the lateral flanges 41, see Fig. 11. The staples 9 are supported on the staple-core 46 in straddled relation thereacross to adapt them to slide within the arm 40 as they are retained thereon by the overlying flanges 41. A staple-pusher 50 of a generally U-shape is mounted in the stapling arm 40 to slide on the top of the staple-core 46. The staple-pusher 50 is urged forwardly under the tension of an elastic cord 51, of latex or the like, having one end connected thereto and extending forwardly around a guide-post 52 riveted or otherwise fastened to the forward end of the arm 40. The cord 51 extends rearwardly from the post 52 with its opposite end connected to a cross-pin 53 at the rearward end of the arm by means of a terminal clasp 54, see Fig. 4. The staples are inserted at the forward end of the arm 40 by forcing the staple-pusher 50 rearwardly against the tension of the cord 51, the pusher acting to feed the staples forwardly when released.

A staple-retainer 57 is provided at the forward end of the arm 40, being adapted to engage the staples 9 and prevent them from sliding forwardly under the action of the staple-pusher 50 while the head 70 is raised or open, see Figs. 11 and 14. The staple-retainer 57 is pivotally mounted on a pin 58 extending between spaced stanchions 59 and 60 on the arm 40, the stanchions being formed integrally with the arm or on a separate element attached thereto. As herein illustrated the stanchions 59 and 60 are formed by the opposite forwardly folded sides of a sheet-metal bracket 61. The upper ends of the stanchions 59 and 60 are arcuately shaped and their lower side portions extend below the connecting web 62 and are offset outwardly to fit closely across the flanges 41 and against the sides of the arm 40, to which they are secured as by brazing, soldering, welding or the like. By this form of

construction a predetermined length of stapling arm 40 may be cut from a longer length of channel-strip for use in a particular machine and the bracket 61 attached thereto, thereby effecting a considerable saving in the material required for manufacture.

The staple-retainer 57 is preferably formed of sheet-metal folded or bent to form a U-shaped element having opposite sides 63 connected by a web 64 and adapted to fit closely between the stanchions 59 and 60. One of the sides 63 of the element 57 is sharpened to form the beak of a pawl 65 which is normally urged into engagement with the staples *s* by a spring 66 coiled about the pivot-pin 58 and having one end engaging the web 64 and its opposite end engaging a suitable abutment. When the pawl 65 is in engagement with the staples *s* as illustrated in Fig. 14 the connecting web 64 is inclined to 20 and projects beyond the forward edges of the stanchions 59 and 60, being adapted to be engaged by the staple-applying mechanism and moved to release the pawl from the staples when the head 70 of the implement is closed on the 25 arm 40.

In accordance with the present invention the stapling head 70 is mounted on the arm 40 for movement toward and away from its end to provide for loading the magazine with a supply of staples at the forward end of the arm. As herein illustrated, the head 70 is pivotally mounted but it is to be understood that the head may be mounted for vertical movement away from the arm 40, for horizontal movement with respect thereto, or for combined vertical and horizontal movement to accomplish the function. In the present preferred embodiment of the invention the head 70 is in the form of a box-like housing having a front wall 71 and rearwardly-extending side walls 72 having their edge portions 73 bent inwardly toward each other. The head 70 is adapted to enclose the stanchions 59 and 60 of the bracket 61 with the lower portion of its front and side walls 71 and 72 engaging the end of the arm 40. A pin 74 extends between the sides 72 of the head 70 and through slots 75 in the stanchions 59 and 60 to pivotally mount the head for movement over the arcuate ends of the stanchions from the position shown in Fig. 12 to that shown in Fig. 14. Arcuately shaped ears 76 and adjacent similarly shaped notches 77 are formed on the lower edges of the opposite sides 72 of the head 70 which cooperate with correspondingly shaped ears or lugs 78 and notches 79 on forwardly-projecting side portions of the bracket 61 in interfitting relationship to latch the head in a closed position with respect to the end of the arm 40. A coiled tension-spring 80 extends between a bent finger 81 on the bracket 61 and the pivot-pin 74 to yieldingly hold the ears 76 on the head 70 in engagement with the notches 79 on the bracket. The spring 80 is adapted to yield to permit the head 70 to be moved upwardly on the stanchions 59 and 60 to release the latching ears 76 and 78 and permit the head to be rocked on the pin 74 away from the end of the arm 40. With the head latched in its closed relationship the lower portion of its front wall 71 cooperates with the end of the arm 40 to form a throat 82 through which the staples *s* are driven into the work. To this end the bottom wall 42 of the arm 40 and the end of the stapling core 46 are cut away to form a space slightly greater than the thickness of the staples 75 *s*, thus leaving forwardly-projecting side walls

on the stapling arm 40, the edges of which are engaged by the front wall 71 of the head 70 when the latter is closed against the arm, see Figs. 12 and 14. The bottom wall 42 of the stapling arm 40 also has rearwardly-extending slots 83 at its forward end adjacent the throat 82 to provide a clearance for the legs of deformed staples to prevent them from jamming as they are driven.

The staple-applying mechanism is carried in the head 70, being adapted to be assembled exteriorly of the implement and slid bodily into the head as a unit. As shown in Figs. 2 and 4, the staple-applying mechanism includes a channel-shaped plunger 85 having side walls 86 engaging the side walls 72 of the head 70 with a close sliding fit and a rearward wall 87 spaced from the front wall 71. The rearward wall 87 terminates short of the ends of the side walls 86 and has a centrally-positioned lug 88 projecting rearwardly therefrom. The rearward edge of one of the extended side walls 86 has V-shaped notches 89 in the nature of ratchet-teeth formed thereon with a clearance slot 90 above the notches, see Fig. 8. The plunger 85 projects upwardly through the open top of the head 70 and has a hand-rest or knob 91 at its upper end.

The staple-driver 92 is mounted in the head 70 between the forward edges of the side walls 86 of the plunger 85 and the front wall 71 of the head 70 and has marginal slots 93 at its edges which interlock with lugs 94 projecting forwardly from the plunger. The upper end of the staple-driver 92 is formed with a projection 95 which engages a slot or opening 96 in the knob 91 while its lower end is reduced to a width equal to that of the staples *s* to adapt it to pass through the throat 82, see Fig. 7. A retaining plate 97 engages the rearward wall 87 of the plunger 85, being formed with a slot 98 through which the rearwardly-extending lug 88 on the plunger extends and an opening at its side overlying the notches 89 in the edge of the plunger. The upper end of the plate 97 has laterally-extending ears 99 seated in slots 100 in the opposite side walls 72 of the head 70 and at its lower end the plate has a forwardly-directed, right-angular extension 101 positioned below the plunger 85. The extended portion 101 of the plate 97 is formed with two parallel slots 102, see Fig. 15, and the metal between the slots 102 bent upwardly to provide a bearing 103 which overlies a retaining pin 104. The two lateral portions 105 of the metal are arched below the pin 104 to connect the plate 97 thereto. The pin 104 extends through the side walls 72 of the head 70 and the arched bent portions of the plate-extension 101 and has its ends riveted or headed over against the sides of the head to permanently mount the plate 97 in position in the head. The center of the extension of the plate 97 is punched to form an upwardly-projecting abutment or seat 106. A spring 107 is mounted in the channel of the plunger 85 with its upper end engaging the knob 91 and its lower end seated on the abutment 106. The spring 107 acts to normally hold the plunger 85 in raised position, the upward movement of the plunger being limited by the engagement of the rearwardly-projecting lug 88 with the upper end of the guiding slot 98 in the retaining plate 97. Suitable spacers 108, see Fig. 70, formed by folded channel strips of sheet-metal are provided in the plunger 85 for holding the spring 107 centrally positioned therein.

To prevent the return of the plunger 85 before it has been moved through a full stroke a pawl 75

109 is pivotally mounted on one of the side walls 72 of the head 70 and arranged for cooperation with the notches 89 on the rearward edge of the side wall 86 of the plunger, see Fig. 8. The pawl 5 109 is held in position to engage the notches 89 by means of a spring 110 extending between a tailpiece 111 on the pawl and a hook 112 formed on the lower end of the wall 73 of the head 70.

To assemble the staple-applying mechanism in 10 the head 70 the spring 107 is first placed in the channel of the plunger 85 between the spacers 108 and the staple-driver 92 applied to the forward edges of the side walls 86 of the plunger with its slots 93 in engagement with the lugs 94. 15 The retaining plate 97 is then placed against the rearward wall 87 of the plunger 85 with the lug 88 extending through the slot 98 and the spring 107 compressed between the abutment 106 and the knob 91. The assembled mechanism is next 20 slid bodily into the open end of the head 70 as a unit and the laterally-extending ears 99 on the plate 97 seated in the slots 100. The pin 104 is then passed through the apertures in the sides 72 of the head 70 and through the bearing 103 after 25 which the ends of the pin are riveted or headed over to retain the parts in assembled relationship.

To load the implement with a supply of staples 30 the head 70 is rocked on its pivot-pin 74 to the position shown in Fig. 14. This is accomplished 35 by first sliding the head 70 upwardly on the stanchions 59 and 60 to release the latching ears 76 from the notches 79, the pivot-pin 74 sliding in the slots 75 against the tension of the spring 80 to accommodate this movement of the head. 40 A supply of staples *s* preferably in the form of a stick, are slid into the magazine in the arm 40 to straddle the staple-core 46 beneath the side flanges 41 on the arm. The staples *s* ride under 45 the pawl 65 of the staple-retainer 57 which yields as the staples are pushed rearwardly into the magazine to force the staple-pusher 50 back. When the stick of staples is released, however, the pawl 65 engages with the staples under the action of its spring 66 to prevent them from being moved forwardly. The head 70 is then rocked on its pivot-pin 74 to the closed position illustrated in Fig. 1.

During the rocking movement of the head 70 the arcuate latching ears 76 on the head 70 ride over the ears 78 on the bracket 61 and cam the head upwardly on the stanchions 59 and 60, the spring 80 yielding to permit the pivot-pin 74 to slide in the slots 75 in the stanchions. The latching ears 76 and 78 slide by each other and yieldingly engage the adjacent grooves 77 and 79 as the spring 80 expands to latch the head 70 in staple-driving relationship with respect to the end of the arm 40. During the final movement of the head 70 to its closed position the rearward face of the retainer plate 97 engages the projecting web 64 of the staple-retainer 57 and rocks the latter on its pivot-pin 58 to release its pawl 65 from engagement with the staples *s*. The implement is then ready for operation and the arm 40 may be moved longitudinally of the base 2 to position the staple-driver 92 in cooperative relationship with either one or the other of the spaced pairs of clincher-grooves 8 or 9. As previously explained, the pivot-pin 45 carried by the arm 40 is slideable 65 in the curved slots 30 and 31 and yieldingly held at either end of the slots by the opposite legs 33 of the U-shaped leaf-spring 32.

The work *w* to be stapled is placed on the anvil 7 and pressure applied on the knob 91 of the plunger 85. This pressure first causes the arm 40

to be rocked on its pivot-pin 45 against the action of the spring-pressed button 36 to engage the forward end of the arm with the upper face of the work. Continued pressure then causes the plunger 85 to be depressed against the action of its spring 107 to slide the staple-driver 92 connected therewith downwardly. As the staple-driver 92 descends its lower reduced end engages the cross-bar of a staple *s* moved to a forward position by the staple-pusher 50 and drives it through the 10 throat 82 and into the work, see Fig. 5. The pair of clincher-grooves 8 or 9 then bend over the legs of the staple into clinching engagement with the underside of the work as shown in Figs. 7 and 13. Upon release of the plunger 85 the 15 spring-pressed button 36 raises the arm 40 and the spring 107 acts between the abutment 106 on the retaining plate 97 and the knob 91 to raise the plunger 85 and staple-driver 92 to first position as shown in Figs. 1 and 4. The upward 20 movement of the plunger 85 is limited by the engagement of the rearwardly-extending lug 88 with the upper end of the slot 98 in the retaining plate 97.

During the descent of the plunger 85 and 25 staple-driver 92 the pawl 109 cooperates with the notches 89 to prevent the plunger from being raised until a full stroke has been completed. At the end of a full stroke of the staple-driver 92 the pawl lies positioned in the clearance slot 90, 30 as illustrated in Fig. 9, to permit it to be reversed in position as the plunger 85 is raised. During the return stroke of the plunger 85 the pawl 109 is rocked upwardly to the position shown in Fig. 10 where it cooperates with the notches 89 to prevent another staple-driving operation until the plunger has completed its full upward stroke. 35

A series of staple-applying operations may be 40 made in the manner explained above either continuously or intermittently until the supply of staples *s* in the magazine is exhausted. To reload the magazine with a fresh supply of staples the head 70 is moved upwardly on the stanchions 59 and 60 and rocked about its pivot-pin 74 in one continuous movement to unlatch the lugs 76 and 78 and carry the head to its open position 45 shown in Fig. 14. Occasionally, due to abusive operation or to a slight defect in a staple, the staple being driven may be caught or jammed in the throat 82. As most staple jams are accompanied by the staple-driver 92 becoming locked in its lowermost position the force applied to the knob 91 to return the staple-driver results in opening the head 70 and releasing the jammed staple. Thus the pivotal mounting of the head 55 renders the implement proof against damage or breakage of its parts due to jams even in the hands of an inexperienced operator.

It will be observed that my invention provides 60 a novel form of stapling implement in which the head carrying the stapling mechanism is movable toward and away from the end of the arm on which it is mounted to provide for loading the magazine with a supply of staples or to provide for adjustment of the parts.

It will further be observed that the staple- 65 driving mechanism in the head is of an extremely simple and compact structure and that it may be assembled exteriorly of the implement to be slid into the head bodily as a unit.

It will still further be observed that because of 70 its simple and compact structure the implement particularly lends itself to economical manufacture and assembly while its mechanism is positive and efficient in operation and adapted for use over 75

long periods of time without repair or replacement of its parts.

While there is herein illustrated and described one preferred embodiment of the invention, it is to be understood that various modifications may be made in the structure and arrangement of the parts of the device without departing from the spirit or scope of the invention. Therefore, without limiting myself in this respect, I claim:

10 1. In a device of the type indicated, an arm for supporting staples, a stapling head mounted on said arm for movement toward and away from its end, said head cooperating with the end of the arm and forming a throat through which the staples are driven, a staple-driver in said head, cooperating means on the arm and head for securing the parts in staple-driving relationship, and a spring acting between the arm and head for yieldingly holding the cooperating securing 20 means in engagement.

2. In a device of the type indicated, an arm for supporting staples, means to advance the staples on the arm to be driven across its end, a stapling head mounted on the arm for movement toward 25 and away from its end, said head cooperating with the end of the arm and forming a throat through which the staples are driven, a staple-driver in said head, and means automatically operated to engage the staples when the head is 30 moved away from the arm and to release the staples when the head is moved into engagement with the end of the arm.

3. In a device of the type indicated, an arm for supporting staples, means to advance the 35 staples into position to be driven across the end of the arm, a stapling head mounted on the arm for movement toward and away from its end, said head cooperating with the end of the arm and forming a throat through which the staples 40 are driven, a staple-driver in said head, a pawl pivotally mounted on the arm, and resilient means for rocking the pawl into engagement with the staples when the head is moved away from the end of the stapling arm, said pawl being engaged by the head and rocked to release the staples as the head is moved into cooperative 45 relation to the end of the arm.

4. In a device of the type indicated, an arm for supporting a supply of staples, stanchions on 50 the sides of the arm at its forward end, a stapling head pivotally mounted on the stanchions for movement toward and away from the end of the arm, said head cooperating with the end of the arm and forming a throat through which the 55 staples are driven, a staple-driver in said head, a pawl pivotally mounted between the stanchions and adapted to engage the staples, said pawl being adapted to be engaged by the head to rock it to release the staples, and a spring for rocking 60 the pawl to engage it with the staples when the head is moved away from the end of the arm.

5. In a stapling machine, an arm, a stapling head, means mounting the stapling head on the 65 arm for movement toward and away from its end, said head having a forward wall cooperating with the end of the arm to form a throat through which the staples are driven, staple-driving means including a pair of relatively movable 70 members with a spring therebetween slidable into said head as a unit, and means for retaining the staple-driving means in the head.

6. A head for a stapling machine comprising a 75 housing having an open end and slots in its opposite walls, staple-driving means in the hous-

ing including a reciprocating plunger, a staple-driver connected to one side of the plunger for movement therewith, a plate on the opposite side of the plunger, said plate having retaining lugs for engaging the slots in the housing and retaining means at its lower end, and a pin extending through the housing and retaining means on the plate for supporting the plate in the housing, said staple-driving means being slidable into the housing as a unit through its open end.

7. In a stapling machine, an arm, stanchions on the arm having elongated slots, a stapling head embracing the stanchions and having a forward wall cooperating with the end of the arm to form a throat through which the staples are driven, stapling mechanism carried by the head, a pin extending through the head and slots in the stanchions for mounting the head for pivotal movement toward and away from the end of the arm and for bodily movement upwardly on the 20 stanchions, interengaging means on the head and arm for latching the head in engagement with the end of the arm, and a spring for holding the interengaging means on the head and arm in latched relationship while yielding to allow the head to be moved upwardly on the stanchions to release the notches from engagement with the lugs.

8. In a stapling machine, an arm, stanchions on the arm adjacent its forward end and having beveled latching lugs at the sides of the arm and elongated slots at their upperends, a pawl pivotally mounted between the stanchions and adapted to engage the staples, a stapling head embracing the stanchions and having a forward wall cooperating with the end of the arm to provide a throat through which the staples are driven and enclosing side walls with notches for cooperation with the latching lugs, a pin extending through the head and slots in the stanchions for 40 pivotally mounting the head for swinging movement toward and away from the end of the arm, a spring connected between the stanchions and pin to hold the notches on the head in engagement with the latching lugs on the stanchions, and staple-driving means in the head adapted to engage the pawl to release it from the staples when the head is moved into engagement with the end of the 45 arm.

9. In a stapling machine, a stapling arm comprising a supporting member of U-shaped cross-section, a staple-core within the supporting member and cooperating therewith to provide a magazine for receiving staples, a stapling head at one end of the arm, and a loop depending from the 55 bottom of the arm adjacent the opposite end and forming a bearing for receiving a pin to pivotally mount the arm, said loop and the bottom of the arm embracing the pin.

10. In a stapling machine, a base having spaced flanges adjacent one end with slots formed therein, clincher-grooves arranged in spaced relation on the base, and a stapling arm having a head at one end and a pin at its opposite end with its ends projecting into the slots in the flanges on the base, 65 said pin and slots pivotally mounting the arm and permitting movement thereof longitudinally of the base to position the stapling head in cooperative relation with either of the clincher-grooves.

11. In a stapling machine, a base having spaced flanges adjacent one end with slots formed therein, a bowed spring on the base having opposite branches projecting upwardly and overlying the slots in the flanges centrally thereof, co-operating pairs of clincher-grooves arranged in spaced 75

- relation on the base, a stapling arm having staple-driving means at one end for cooperation with the clincher-grooves and depending loop at its opposite end, and a pin extending through the slots 5 in the flanges on the base and the depending loop on the arm for pivotally mounting the latter on the base, said slots permitting movement of the arm longitudinally of the base to position the stapling head in cooperating relation with either 10 of the clincher-grooves and the branches of said spring acting to hold the arm in either one or the other of its operative positions.
12. In a device of the type indicated, a stapling arm open at its forward end to receive a supply 15 of staples, a core in the arm for supporting the staples, a stapling head having a front wall cooperating with the end of the arm to form a throat through which the staples are driven, means above the core for pivotally mounting the head on 20 the arm to adapt it for swinging movement toward and away from the end of the arm, interengaging means on the arm and head for latching the head in closed position on the arm, and a staple-driver carried by the head and reciprocable in said throat to drive staples advanced 25 along the core.
13. In a fastener-applying device, a support in the form of a magazine for holding a supply 30 of fasteners, a fastener-applying unit having means for driving the fasteners into the work, means for pivoting said fastener-applying unit to rock on an axis located above the support, and means for releasably retaining said fastener-applying unit in position overlying the end of 35 the support and forming a closure for the magazine therein.
14. In a fastener-applying device, a support, a fastener-applying unit adapted to cooperate with said support to form a throat through which 40 the fasteners are driven, fastener-driving means in said unit, means for pivotally mounting said fastener-applying unit to rock on an axis located above the support whereby it may be opened away therefrom to clear the throat of jammed fasteners, and means for normally retaining the fastener-applying unit in cooperative relation to the support. 45
15. In a fastener-applying implement, a hollow magazine for containing a supply of fasteners, said magazine being closed at the bottom, top and sides and open at one end, a fastener-applying unit having a portion cooperating with the end of the magazine to form a throat through which the fasteners are driven, means for pivoting said unit to rock on an axis above the magazine to open the end of the latter for the insertion of fasteners, and means for releasably holding said unit in position to close the end of the magazine and form the throat for the fasteners. 50
- 60 16. In a device of the type indicated, a magazine for holding a supply of fasteners, means for pivotally mounting the magazine at its rearward end, a self-contained fastener-applying unit, means connecting the unit to the forward end of the magazine to adapt it for movement relatively thereof to open the end of the magazine to permit fasteners to be supplied thereto, said unit having a front wall cooperating with the end of the magazine to form a throat through which the fasteners are driven, and interengaging means on the magazine and unit for releasably holding the latter in cooperative relation to the end of the magazine to form the throat. 55
17. In a device of the type indicated, a magazine-arm for holding a supply of fasteners, means at the rearward end of the arm for mounting it for pivotal movement, a self-contained fastener-applying unit, means at the forward end of the arm for connecting the unit thereto to adapt it for relative movement thereon, said unit having a front wall cooperating with the end of the arm to form a throat through which the fasteners are driven, and means for releasably holding the unit in cooperative relation to the end of the arm, said unit being movable away from the end of the arm to open the same whereby fasteners may be supplied to the magazine. 60
18. In a device of the type indicated, a magazine-arm for holding a supply of fasteners, means at the rearward end of the arm for mounting it for pivotal movement, a self-contained fastener-applying unit, means at the forward end of the arm connecting the unit thereto, said connecting means being so constructed and arranged as to adapt the unit for movement on the arm to close its end and form a throat through which the fasteners are driven, and means for releasably holding the unit in cooperative relation to the end of the magazine-arm, said holding means being releasable to adapt the fastener-applying unit to move away from the end of the arm whereby fasteners may be applied to the magazine. 65
19. In a device of the type indicated, a magazine-arm for containing a supply of fasteners, means for pivotally mounting the arm at its rearward end, a self-contained fastener-applying unit, means at the forward end of the arm for connecting the fastener-applying unit thereto to adapt it for relative movement thereon to permit fasteners to be supplied to the magazine, said unit having a front wall cooperating with the end of the arm to form a throat through which the fasteners are driven, cooperating latching means on the arm and fastener-applying unit for releasably holding the latter in cooperative relation to the end of the arm to form the throat, and resilient means for yieldingly holding the latching means in engagement. 70
20. In a device of the type indicated, a magazine-arm, means for pivotally mounting the arm adjacent its rearward end, a self-contained stapling unit, means at the forward end of the arm for pivotally mounting the unit thereon, said unit cooperating with the forward end of the arm to form a throat through which the staples are driven, and means for releasably holding the unit in cooperative relation to the end of the arm, said unit being adapted to swing on its pivot away from the forward end of the arm to permit staples to be supplied to the magazine. 75
21. In a device of the type indicated, a magazine-arm open at one end, means for pivotally mounting the arm at its opposite end, a hollow housing connected to the arm adjacent its open end for relative movement thereon, said housing having a front wall cooperating with the end of the arm to form a throat through which the fasteners may be driven, interengaging means on the arm and housing for releasably holding the latter in cooperative relation to the end of the arm, said housing being movable away from the end of the arm to permit fasteners to be supplied to the magazine, and fastener-applying mechanism in the housing. 80

JOHN F. CAVANAGH.
